CLAIM

The ornamental design for medical fluid infusion pump, as shown and described.

DESCRIPTION

FIG. 1 is a front perspective view of a medical fluid infusion pump.

FIG. 2 is a top view of thereof.

FIG. 3 is a bottom view thereof.

FIG. 4 is a front view thereof.

FIG. 5 is a back view thereof.

FIG. 6 is a left side view thereof; and,

FIG. 7 is a right side view thereof.

The dash-dash lines in FIGS. 1-7 form no part of the claimed design.
